· sample No. 552.

C. Cheyne's Design for Cast Glass Front.

Patented 19th April 1853.

Wes. 552

Charles Chinnock, of New York, N.Y.
Letters Patent No. 552. Dated April 19th 1853.

The schedule referred to in these Letters Patent and making part of the same

To all whom it may concern:

Be it known that I, Charles Chinnock, of the City, County and State of New York, have invented or produced a new and original design for Cast Metal fronts of Clock Cases; and I do hereby declare that the following is a full and exact description of the same reference being had to the accompanying drawings forming part of this specification in which

Fig: 1, is a front view

Fig: 2, is a side or profile view

Fig: 3, is a vertical profile section taken through the centre

Fig: 4, is a horizontal section taken in the line x. x. of Fig: 1.

Fig: 5, is a horizontal section taken in the line +. +. of Fig: 1, and

Fig: 6, is a horizontal section taken in the line **. **. of Fig: 1.

Similar letters of reference indicate corresponding parts in each

of the several Figs.

The front consists of a plate of about uniform thickness throughout, having two openings, one A, for the clock face, and another, B, through which to adjust the pendulum. The lower part projects some distance in front of the upper part of the plate to form a pediment, C, which terminates in two scroll shaped feet, D. The lower opening B, is in the pediment. The upper part of the plate above the pediment is slightly concave around the opening A, in order to make the clock face stand out with a prominent appearance, and from the concavity a. a. rise the ornaments b. c. d. which form an ornamental border. The form of the several ornaments

Ms. 552

will be better understood by reference to the drawings than by other description. The plate is intended to be ornamented on its face in any manner to suit the taste, and be made to imitate papier-mâché, wood or any other substance.

What I claim as my invention or production is the design and configuration of the plate as described and represented in the accompanying drawings, forming the front of a Clock Case.
